UNITED STATES PATENT OFFICE.

ISAAC L. LESTER AND JOSIAH WHITTLY, OF WHITEHEAD, TEXAS.

COTTON PLANTER AND CHOPPER.

SPECIFICATION forming part of Letters Patent No. 390,241, dated October 2, 1888

Application filed July 3, 1888. Serial No. 278,903. (No model.)

To all whom it may concern:

Be it known that we, ISAAC L. LESTER and JOSIAH WHITTLY, citizens of the United States, residing at Whitehead, in the county of Cherokee and State of Texas, have invented a new and useful Improvement in Combined Cotton Planters and Choppers, of which the following is a specification.

Our invention relates to an improvement in combined cotton planters and choppers; and it consists in the peculiar construction and combination of devices, that will be more fully set forth hereinafter, and particularly pointed out in the claims.

15 In the accompanying drawings, Figure 1 is a top plan view of a combined cotton chopper and planter embodying our improvements. Fig. 2 is a vertical longitudinal sectional view of the same, taken on the line $x-x$ of Fig. 1. 20 Fig. 3 is a vertical transverse sectional view of the same, taken on the line $y-y$ of Fig. 1. Fig. 4 is a detail view.

25 A represents a rectangular frame, which comprises a pair of side beams, B, connected near their front ends by the cross-beam C, and connected near their rear ends by a cross-beam, D.

30 E represents a shaft, which is journaled in the beams B, at a suitable distance from the front end thereof, is provided with wheels F and G, which are of the same size, and has near its center a seed-wheel, H, which is provided with serrated teeth I.

35 K represents a longitudinal beam, which connects the bars C and D, and is arranged at a suitable distance from the center of the frame. In that portion of the beam which is over the seed-wheel is a vertical opening, in which is secured the lower end of the hopper 40 L, the latter having a discharge-opening of suitable dimensions in its lower side, into which projects the upper side of the seed-wheel H. On the inner side of the wheel F is secured a gear-wheel, M, which is provided with crown-teeth.

45 N represents a pair of hounds, which project forward from the beam C, and between which is pivoted the rear end of a tongue or pole to which the draft-animals are hitched in the usual manner.

P represents a pair of furrow-openers, which are arranged in proximity to each other and

have their upper ends provided with vertical slots R, and secured to the center of the beam C, to the front side thereof, by means of clamping-bolts S, which work in the said slots and extend through the said beam. 55

T represents a pair of handles, which are similar to plow-handles, have their front ends secured to the outer sides of the beams B, and are supported in an inclined position by means of a pair of vertical standards, U, which extend from the rear end of the frame, and the said handles are connected together by means of a cross bar or rung, V, the ends of which 60 65 pass through openings in the upper ends of the standards and in the handles.

W represents a lever, which has its front end pivoted to the under side of the cross-beam C, at a suitable distance from the center thereof, 70 and has its rear end curved upward and supported on the rung or bar V, as shown. Projecting from one side of the lever W, near the front end thereof, is an arm, X, which is arranged in a horizontal plane. 75

On the front side of the beam D, near the center thereof, is secured a vertical guideway, Y, in which is arranged a vertically-movable plate, Z. Projecting from the upper side of the cross-bar D is a pair of ears, A', between 80 which, on a suitable pivotal bolt, B', is fulcrumed a lever, C', the front end of which is provided with a hook that engages an opening in the upper end of the plate Z.

D' represents a pair of arms, which project 85 forward from the plate Z, diverge slightly at their outer ends, and are connected by means of a semicircular open cam, E'. The said arms are arranged in a horizontal plane and the said cam extends upward from the front ends thereof, as shown. 90

F' represents a longitudinal shaft, which has its front end journaled loosely in a bearing arranged under the beam C, and has its rear portion passed through the open cam E', the 95 extreme rear end of said shaft being journaled in an opening in the plate Z, whereby the said rear end of the shaft, together with the cam and the arms which carry it, may be raised or lowered by operating the lever C', so as to raise 100 or lower the plate Z, for the purpose to be hereinafter described. The front portion of the said shaft passes through an opening which is made in the arm X, near the free end

thereof, and on the said shaft is rigidly secured a pinion, G', which meshes with the crown-wheel M.

- H' represents a pair of spring bars or arms, 5 which have their front ends secured to the rear side of the pinion G' on diametrically-opposite sides thereof, and to the rear ends of the said spring bars or arms are secured a pair of S-shaped arms, I', which are arranged substantially at right angles to the spring bars or arms, and have chopping-hoes K' secured to their outer ends. The length of the spring bars or arms is such that the same, near their free ends, come into contact with the cam. 15 L' represents a pair of curved plow-beams, which have hooks at their front ends that engage eyes or keepers on the center of the beam D, and said plow-beams are connected rigidly together by means of a cross-bar, M'. 20 To the lower rear ends of the plow-beams are secured cultivating shovels or coverers N', and projecting rearward from the center of the cross-bar M' is a curved lever, O', by means of which the cultivating shovels or coverers may 25 be caused to work in the ground at any desired depth.

P' represents a driver's seat, which may be employed when the machine is used for planting cotton, and is supported above the 30 lever C' and O' by means of spring-arms R', which have their lower front ends rigidly secured to the beams B.

The operation of our invention is as follows: When the machine is used for planting cotton, 35 the hopper is filled with cotton-seeds, and the lever W is moved to the position indicated in dotted lines in Fig. 1, so as to cause its arm X to move the front end of the shaft F' laterally a sufficient distance to cause the pinion G' to 40 be disengaged from the wheel M, and thereby cause the said pinion to remain at rest. As the machine advances, the wheels F and G rotate the shaft E and the seed-wheel, which works in the hopper, and cause the said seed-wheel to draw the cotton-seeds from the hopper and drop them into the furrow made by the furrow-openers. The plows, which are attached to the rear end of the frame, cover the seeds in the furrow. The furrow-openers, 50 being vertically adjustable by reason of their slots R and the clamping-bolts S, may be caused to open furrows of any desired depth. When it is desired to use the machine for chopping cotton and cultivating the same, the furrow-openers are removed, the lever W is 55 arranged in the position shown in solid lines in Fig. 1, so as to cause the arm X to move the shaft F', so as to engage the pinion G' with the wheel M, and the lever C' is operated so 60 as to raise or lower the plate Z to the height necessary to cause the chopping-hoes to enter the ground to the desired depth. As the machine advances, the rotation of the wheel M causes accelerated rotary movement in the 65 pinion G', and the spring-arms, which are attached to said pinion, are caused to whirl with the shaft F'. While each spring-arm in suc-

cession is describing the upper half of its orbit it is in engagement with the curved upper side of the cam, and is maintained with 70 its free rear end at a considerable distance from the shaft, and as each spring-arm clears the lower side of the cam as it describes the lower half of its orbit it springs toward the shaft, and thereby causes the hoe attached 75 thereto to engage the ground and enter the same in a manner very similar to the motion imparted to an ordinary hoe when manipulated by hand. As each hoe in succession enters the ground, it chops out the cotton-plants which 80 are in its path, thereby leaving "stands" of cotton at suitable regular distances apart along the row. The shovels or plows which operate in rear of the machine serve to stir and pulverize the soil on both sides of the row of 85 plants, and thereby cultivate and promote the growth of the same.

Having thus described our invention, we claim—

1. The combination, in a cotton-chopper, of 90 the frame having the driving-wheel provided with the gear M, the cam supported by the frame, the longitudinal shaft F, the pinion G' on said shaft and engaging the wheel M, and the spring-arms having the hoes at their rear 95 ends and having their front ends attached to the pinion, said spring-arms being adapted to engage the cam, for the purpose set forth, substantially as described.

2. The combination of the frame, the driving-shaft having the wheel M, the vertically-movable plate Z on the rear end of the frame, the shaft F', having its front end journaled to the frame and its rear end journaled in the plate Z, the cam supported by arms projecting 105 from the said plate, the pinion on the shaft F' and engaging the wheel M, and the spring-arms having their front ends secured to the pinion and having their rear ends provided with the chopping-hoes and adapted to engage the cam, for the purpose set forth, substantially as described. 110

3. The combination, in a cotton-chopper, of 115 the frame, the driving-shaft having the wheel M, the longitudinal shaft F', arranged in the frame and having its front end laterally movable in its bearing, the cam arranged concentric with the shaft F', the pinion on said shaft, and the spring-arms attached to the pinion and having the chopping-hoes at their rear end 120 and adapted to engage the cam, and the lever connected to the front end of the shaft F', to move the same laterally, so as to cause the pinion to engage or disengage the wheel M, substantially as described. 125

4. The combination, in a cotton-chopper, of 130 the frame, the driving-shaft journaled therein and having the wheel M, the vertically-movable plate Z at the rear end of the frame, and having the arms projecting forward therefrom, and the semicircular cam supported by said arms, the shaft F', having its rear end journaled in said plate and its front end laterally movable in its bearing, the pinion on said

shaft, the spring arms projecting rearward from the pinion and having the chopping-hoes attached to their rear ends, the lever to raise and lower the plate Z, and the laterally-movable lever W, having the arm X at its front end engaging the front end of shaft F, whereby the latter may be moved, so as to cause the pinion G' to engage or disengage the wheel M, substantially as described.

10 In testimony that we claim the foregoing as

our own we have hereto affixed our signatures in presence of two witnesses.
